INVENTOR,
MALVIN LICHTER

Walton Harrison
ATTORNEYS.

UNITED STATES PATENT OFFICE.

MALVIN LICHTER, OF NEW YORK, N. Y.

MEASURING-SHEET FOR PREPARING PRINTING-PLATES.

1,372,174.

Specification of Letters Patent. Patented Mar. 22, 1921.

Original application filed October 23, 1919, Serial No. 332,695. Divided and this application filed December 3, 1919. Serial No. 342,125.

To all whom it may concern:

Be it known that I, MALVIN LICHTER, a citizen of the United States, residing at New York city, county of New York and State of New York, have invented certain new and useful Improvements in Measuring-Sheets for Preparing Printing-Plates, of which the following is a full, clear, and concise description.

10 My invention relates to measuring sheets to be used upon typewritten matter, my purpose being to provide a sheet of transparent material having to some extent the function of a gage, and used as hereinafter described. This sheet of transparent material is provided with indicating marks so arranged as to enable the sheet to be laid upon and preferably secured to a sheet of typewritten matter, and there so used as to 15 indicate directly to the operator any differences in the lengths of the several typewritten lines, and to indicate the shortages, if any, of such typewritten lines as compared with a standard line of predetermined length.

More particularly stated I seek to produce a measuring sheet of the kind just mentioned, and in which the indicating marks are so spaced apart and otherwise arranged as to 20 enable the operator to read off line by line at a glance the precise number of spaces, each of the width of a letter made by a standard typewriting machine, which if added to the respective typewritten lines 25 would render them all of said predetermined or standard length.

I seek to render my measuring sheet suitable for use as an article of manufacture, and to give it such form and arrangement 30 that its use upon typewritten sheets in the manner here contemplated is accomplished without necessitating the marking or mutilation of such sheets.

This application is a division of my 35 pending application filed Oct. 23, 1919, Serial No. 332,695, for a method of preparing plates for printing.

Reference is made to the accompanying drawing forming a part of this specification,

and in which like reference characters indicate like parts throughout all of the figures.

Figure 1 is a fragmentary plan view of my improved measuring sheet.

Fig. 2 is a fragmentary plan view of a sheet of typewritten matter, upon which the measuring sheet is to be used.

Fig. 3 is a fragmentary plan view showing the measuring sheet as applied to the typewritten sheet appearing in Fig. 2.

Fig. 4 is a fragmentary plan view of a typewritten sheet, made by copying line by line the typewritten matter of the sheet shown in Fig. 2, but in which the spacing is corrected so as to render the lines of uniform and predetermined length.

A sheet of transparent material, in this particular instance celluloid, is shown at *a* and is made of sufficient size to fully cover a typewritten sheet of the kind upon which the measuring sheet is to be used. A number of score lines *b*, *c* are carried by the measuring sheet, the score line *b* being spaced a little distance from the edge of the sheet to the left according to Fig. 1. The score lines *c* are disposed in proximity to the edge to the right according to Fig. 1 and are parallel to each other. The score lines *c* are separated by spaces each of the exact width of a letter or other character as ordinarily made by a standard typewriting machine. The score line *b* is separated from the nearest one of the score lines *c* by a distance equal to an exact multiple of the width of a letter, and hence it follows that each score line *c* is spaced from the score line *b* by some exact multiple of such letter.

Between the lines *c* are numerals 1 to 9 inclusive, repeated at intervals and arranged in groups *d*, *e*, *f*, *g*, *h*, *k*, as shown in Fig. 1.

The lines *b* and *c* and all of the numerals in the various groups are preferably rather sharply defined, and the numerals should have such form as to be readily distinguishable from such characters as may be made upon a typewriting machine.

The score lines and numerals thus carried by the measuring sheet constitute indicating

marks upon which the operator can make his readings.

In Fig. 2 is shown a sheet of paper *l*, carrying typewritten matter *m*, arranged in the conventional manner well known in this art, the typewritten lines thus varying in length, and the variations being apparent at the right hand side of the sheet as shown in this figure.

10 If, now, the measuring sheet be laid flat upon the sheet of paper shown in Fig. 2, so that the score line *b* is brought into exact registry with the beginnings of the respective lines, as shown in Fig. 3, it follows that each letter or character ending a typewritten line is shown in some one of the longitudinal spaces designated by the numerals 1 to 9 inclusive.

15 The operation of my device is as follows: 20 The paper sheet of typewritten matter, say the sheet *l* shown in Fig. 2, is spread out and the measuring sheet is placed upon it and brought into proper registry with it, as just described, so that the operator, looking through the transparent measuring sheet at the typewritten lines, can see the endings of the typewritten lines in the various longitudinal spaces designated by the numerals. This done the operator can determine by casual glances all differences in the lengths of the typewritten lines, these differences being read off in units, each unit being the width of a typewritten letter or other typewritten character.

30 35 Moreover, in doing this the operator is enabled at the same time to determine the shortage, if any, of each of the typewritten lines from the predetermined length of a straight line, namely, the particular score line at the extreme right. This line is so located, relatively to the score line *b*, as to delineate the maximum length of line which can be written upon the typewriting machine, when the machine is adjusted for use 40 45 upon the sheet shown in Fig. 2.

Thus the operator can ascertain, line by line of the typewritten matter, just how many spaces are required to be employed in each line, as it is being copied upon a new sheet *n* as shown in Fig. 4, in order to render all of the typewritten lines of uniform length, as shown at *o* in this figure.

50 55 In practice the operator, after bringing the measuring sheet into proper registry with sheet *l* as shown in Fig. 3 and as above described, merely treats the sheet *l*, with the measuring sheet upon it, as a piece of copy, and upon this piece of copy, the sheet *n*, shown in Fig. 4, is made. This sheet *n* thus 60 65 has its lines all of the same length, which is the length of a predetermined standard line.

The finished sheet shown in Fig. 4 may be used as an original copy sheet, for the 65 production of a printing plate by the photo-

olithographic process or by a photoengraving process. Such use of the sheet *n*, however, is not essential to my invention.

Having thus described my invention, what I claim as new and desire to secure by Letters Patent is as follows:

1. As an article of manufacture, a sheet of transparent material provided with a number of sight lines disposed parallel to each other, and also parallel to one edge of the sheet, each of said lines having a length substantially equal to the length of the sheet, said lines being separated by spaces each of the precise width of a standard typewritten character. 75 80

2. As an article of manufacture, a member of transparent sheet material provided with a group of indicating lines, some of said indicating lines being spaced apart by distances each of the precise width of a letter made by a standard typewriting machine, said member of sheet material being further provided with another indicating line separated from said group by a distance approximately equal to the length of a typewritten line, said distance being an exact multiple of the width of said letter. 85 90

3. As an article of manufacture, a sheet of transparent material provided with indicating lines disposed parallel with each other, and spaced apart by distances each representing the precise width of a letter made by a standard typewriting machine, said indicating lines each having a length extending substantially the full length of the sheet, said sheet being further provided with indicating marks for defining said spaces between said indicating lines. 95 100

4. As an article of manufacture, a sheet of transparent material provided with a number of indicating lines disposed parallel to each other and arranged in a group, said indicating lines each having a length approximating the length of the sheet, said indicating lines being spaced apart by distances each of which is an exact multiple of the width of a single letter made by a standard typewriting machine, said group as a whole being spaced from one edge of said sheet by a distance approximating the length of a line of typewritten matter. 105 110 115

5. As an article of manufacture, a sheet made of transparent celluloid and provided with an indicating line disposed adjacent one of its margins, and with a plurality of other indicating lines grouped together and disposed adjacent another one of its margins, said last mentioned indicating line being spaced apart by distances each equal to the precise width of a letter made by a standard typewriting machine, said last mentioned indicating lines being spaced from said first mentioned indicating line by a blank space free of lines and having an aggregate width which is an exact multiple 120 125 130

of the width of the letter made by a standard typewriting machine.

6. As an article of manufacture, a transparent member having the form of a sheet and provided with a straight edge, said member being further provided with a number of indicating lines disposed parallel to

said edge and to each other, said lines each extending a considerable distance in the direction of the length of the sheet, said lines being spaced apart by distances each of the width of a letter made by a typewriting machine.

MALVIN LICHTER.
